US00D865030S

(12) **United States Design Patent** (10) **Patent No.:** **US D865,030 S**
(45) **Date of Patent:** **** Oct. 29, 2019**

(54) **CAMERA**

- (71) Applicant: **Sony Corporation**, Tokyo (JP)
(72) Inventor: **Noriaki Takagi**, Kanagawa (JP)
(73) Assignee: **SONY CORPORATION**, Tokyo (JP)
(**) Term: **14 Years**
(21) Appl. No.: **29/525,137**
(22) Filed: **Apr. 27, 2015**

Related U.S. Application Data

- (63) Continuation of application No. 29/435,722, filed on Oct. 26, 2012, now Pat. No. Des. 727,993, which is a continuation of application No. 29/371,147, filed on Oct. 29, 2010, now Pat. No. Des. 669,930, application No. 29/525,137, which is a continuation of application No. 29/470,895, filed on Oct. 25, 2013, now Pat. No. Des. 750,149, which is a continuation of application No. 29/421,668, filed on Aug. 31, 2012, now Pat. No. Des. 694,800, which is a continuation of application No. 29/371,171, filed on Nov. 10, 2010, now Pat. No. Des. 667,039, application No. 29/525,137, which is a continuation of application No. 29/455,190, filed on May 17, 2013, now Pat. No. Des. 810,809, which is a continuation of application No. 29/371,991, filed on Apr. 9, 2012, now abandoned, which is a continuation of application No. 29/371,171, and a continuation of application No. 29/371,609, filed on May 16, 2011, now Pat. No. Des. 657,409, application No. 29/525,137, which is a continuation of application No. 29/482,643, filed on Feb. 20, 2014, now Pat. No. Des. 749,163, which is a continuation of application No. 29/371,747, filed on Aug. 23, 2011, now Pat. No. Des. 701,552, which is a continuation-in-part of application No. 29/371,149, filed on Oct. 29, 2010, now Pat. No. Des. 648,363.
